BED DAVENPORT

Homer W. Young, Springfield, Mo.

Application September 8, 1941, Serial No. 410,064

8 Claims. (Cl. 5—31)

My invention relates to a bed-davenport and particularly to a convertible device of this character in which provisions are made for utilizing a full-width, full-thickness innerspring mattress, such as commonly used on standard stationary beds.

The principal object of my invention is to provide a convertible bed-davenport of this type and using such a full-sized mattress without increasing the seat and back dimensions of the davenport beyond comfortable limits and pleasing appearance.

Another object is to provide a davenport of this type which includes a bed member having suitable frame and spring means separate from the seating members (which require a different type of springs for comfort) and whereby the bed is not used as a seat nor the seat used as a bed.

Another object is to provide a davenport of this type which facilitates the convenient placing of bedding material such as quilts, blankets, pillows, etc., on the front of the mattress prior to closing the device into a davenport and whereby such bedding material is carried by the mattress to a position under the seat, thus eliminating any awkward stuffing or cramming of such materials into inconvenient compartments.

A further object of the invention is to provide a mode of operation in which conversion from a davenport to a bed or vice versa is accomplished in more than a single operation in order to divide the work into easy stages and eliminate excessively difficult operation.

Another object is to provide a bed-davenport which may remain disposed against a wall of a room when converted into a bed, and which when opened into a bed does not leave the rear edge of the bed portion disposed against such wall nor in close juxtaposition to a back rest or other obstruction, such provision facilitating the draping of bed covers over the edge of the bed.

Another object is to provide a bed or sleeping portion at a higher level than the seat of the closed davenport.

A further object is to provide a bed-davenport in which the moving parts are counterbalanced throughout their movement and in which a minimum amount of springs, levers, links, etc., are employed.

Another object is to provide a bed-davenport in which the bed sections are carried principally by rollers operating upon tracks and which cooperate to convey the sections from a stored position within the closed davenport to a bed position when open.

Other objects are to provide means for utilizing a reversible mattress without seams, joints, ridges or depressions and which is uniformly sprung throughout, such means being capable of handling a mattress of this type without excessively acute bending of the mattress and which in folding is raised simultaneously at the front and back edges during the initial operation whereby the mattress will be flexed prior to being shifted into its final position thereby preventing any inclination of the mattress to slip or become dislocated on the frame of the bed and eliminating the necessity of fastening the mattress to the bed-frame.

15 In the accomplishment of these objects I have provided a stationary main frame or housing, a seat member adapted to be turned over forwardly into an inverted position in front of the main housing, a mattress or bed frame comprising 20 articulated sections, the rear section of which carries at each end a pair of spaced rollers adapted to engage tracks carried by the end members of the housing, the tracks being so shaped and disposed that when the rollers traverse the tracks the bed section will be carried from a vertical position at the rear of the housing to a horizontal position at bed height; a back rest hinged at its top to the rear bed section and held in an upright back-rest position when the bed section 25 is vertically disposed and which is adapted to be carried by the bed section to a horizontal position when the latter is so disposed, after which it may be swung backwardly out of the way; a central bed-section articulated with the rear section and having centrally of each end rollers 30 which engage tracks carried by the housing end members and adapted to carry this section from an inclined position at the rear and bottom of the housing to a horizontal position forwardly 35 of the rear section and on a level therewith; a front bed-section articulated with the central section and adapted to be raised at the front from a position at the bottom of the housing and to be pulled forward together with the other 40 sections into a co-planar horizontal position with the front section resting upon supports carried by the inverted seat member; links interconnecting the front bed section with the seat member at each end and adapted to raise the front edge 45 of the front bed-section to approximately bed-height when the seat is inverted after which the links act as guides for the front section as it is swung forwardly on the links to its final forward position, bringing the entire bed frame into horizontal position; and a spring means for aiding in 50 55

lifting the seat member from a seat position and also aiding in balancing the parts during other operations.

In the drawings, Fig. 1 is a fragmentary perspective view of my device; Fig. 2 is a vertical section taken on 2—2, Fig. 1, showing the device as a seat; Fig. 3 is a vertical section corresponding with Fig. 2, and showing the device opened as a bed; Fig. 4 is a fragmentary horizontal section taken on 4—4, Fig. 3; Fig. 5 is a fragmentary front view showing the device opened; Fig. 6 is a vertical section showing hinge for back rest member; Fig. 7 is a longitudinal section taken on 7—7, Fig. 6 showing hinge and roller supporting means; Fig. 8 is a vertical section taken on 8—8, Fig. 3, showing roller supporting means; Figures 9, 10, 11 and 12 are diagrammatical views showing the action of the device and representing operative positions intermediate the closed position of Fig. 2 and the open position of Fig. 3.

Throughout the various views the same numerals represent similar parts.

In more detail and with reference to the drawings a frame, or housing is provided including end walls 1, a back panel-board 2, a front panel-board 3, a floor 4 and a horizontal brace 5. The end walls and front panel board are upholstered with suitable material 6 and 7 respectively. A cloth back 8, serves to complete the housing into a dust-proof compartment when the device is closed.

The walls 1 at each end of the davenport support tracks 9, 10 and 11 for carrying the hinged bed frame which is provided with rollers 12, 13 and 14 at each end for engaging the tracks. The bed frame comprises three sections, hinged through the end members 15, 16 and 17 for articulation and forming rear, middle and front sections respectively. Members 15 at either end of the bed are joined longitudinally by the rear rail 18, while the members 17 are interconnected by a front rail 19. End members 16 are joined by a brace 20 which maintains parallelism between the members 17 and is underslung to provide room for depression of the spring fabric 21 carried by the bed frame. The spring fabric 21 may be of any conventional type and is designed to support a standard innerspring mattress indicated by the dotted lines 21A, representing the mattress in phantom. 22 is an upholstered back rest which has end members 23 attached to brackets 24 pivoted on the roller supporting studs 25, (Figs. 6 and 7 show this feature in detail). Longitudinal members 26 and 27 attached at each end to the brackets 24 form a top member for the back rest while a longitudinal member 28 forms a bottom member for the back rest. Springs 29 of the well known "No-Sag" type (disclosed in Patent No. 2,002,399 issued by the U. S. Patent Office) span the space from the top to the bottom members of the back rest to form a spring base for the padding assembly 30.

31 is an upholstered seat which has end members 32, a front rail 33 attached to the angle bar 34 and a rear rail 35 attached to the angle bar 36. The angle bars are secured to the end members 32 to form a seat frame and springs 37 having hooked ends which engage openings in the angle bar 36 are secured at the front to the rail 33 and form a base for the coil springs 38 which support the padding assembly 39.

Hinges 40 interconnect the front panel board 3 and the front angle bar 34 whereby the seat is articulated with the housing of the device so it

may be swung forward to form a support for the bed frame when in the open position as a bed.

Hooks 41 secured to each end of the frame 5 of the back rest engage lugs 42 attached to the end members 32 of the seat frame to provide a rear support for the seat when the latter is disposed in seating position.

Levers 43 pivoted at 44 to the end walls 1 and carrying rollers 45 which engage the lower edge of the seat end members 32 urge the seat upwardly through the springs 46 providing a balance for the weight of the seat and facilitating lifting it from the seating position.

Links 47 pivoted at one end to the seat end members 32 at 48 and to the front ends of the front bed sections 17 at 49 provide supporting means for the front bed section.

50 is a hand strap by which the seat may be operated.

It will be noted that the back rest is supported entirely by the bed frame through the studs 25 which carry the rollers 12 and that the back rest is pivoted on these studs so that its end members 23 may rest against the bed frame member 15, thus the back rest moves with the bed frame when the latter is transferred from a vertical to a horizontal position and vice versa.

It is also noted that the bed frame is supported entirely by the rollers 12, 13 and 14 (preferably of the ball bearing type) and by the links 47 while being moved from one position to another. The rollers 12 and 13 carried by members 15 and being guided and supported by the tracks 9 and 10 respectively maintain a positively controlled relation between the members 15 and the housing of the device throughout its movement from a vertical position to a horizontal position. The intermediate frame members 16 being articulated at their rear ends with the frame members 15 and being supported centrally through the rollers 14 by the tracks 11 also maintain a positive relation with the rear section members and with the housing of the device throughout the movement from a seat position to a bed position. The front section members 17 being articulated with the central sections 16 and having their front ends carried by the links 47 also maintain a positive correlation with the other parts throughout their travel.

The end members 32 of the seat carry legs 51 adapted to slide within the supports 52 and 53, the legs being retained by the foot portion 54 and the flange 55 carried by the leg. A weighted catch 56 is loosely pivoted on the pin 57 and moves freely within a slot formed in the seat end member 32 (shown in section in Fig. 3). When the seat is turned forward the legs 51 slide downward to extend the footed end to form a support for the seat unit while the catch 56 by its own weight assumes a position to engage the flange 55 of the leg, locking the latter in position. When the seat unit is turned backward the catch 56 disengages the flange 55 and the leg slides downward, the footed end receding below the level of the seat surface.

Studs 58 projecting outwardly of the seat ends 32 are adapted to be engaged by the links 47 to limit the movement of the latter.

70 Rollers 13 and 14 are carried by supports 59 and 60 respectively (shown in detail in Fig. 8).

In operation from a seat or closed position as Fig. 2 the seat is raised (aided by the springs 46) as in Fig. 9 whereby through the links 47 the front edge of the front bed-section is lifted

to a point in line with the hinges 40 whereupon the links 41 engage the studs 58. Further movement of the seat unit forwardly and downwardly as in Fig. 10 causes the links 41 to pull the front bed section forwardly slightly which simultaneously brings the other bed sections into new positions. The front portion of the middle section in moving forward is caused to rotate somewhat on the axis of the rollers (the rollers moving from the inclined rear portion of the track 11 to the central horizontal portion), while the rear section is lowered and at the same time brought forward but retains approximately a vertical position (the top is brought forward sufficiently to clear the brace 5, due to the inclined portion of track 9 near the top thereof). The rear portion of track 10 is inclined whereby in cooperation with the inclined upper portion of track 9 the vertical disposition of the back rest and rear bed section is maintained throughout this phase of the opening operation.

The second operation is made by pulling forward and upward on the front rail 19 of the bed frame whereby (see Fig. 11) the middle bed section, carried by rollers 14 operating upon the horizontal portion of tracks 11 is rotated in its forward movement to a horizontal position and the rear section is carried downward and its lower portion moved considerably forward on the inclined portion of tracks 10 (the upper portion of the rear section being guided by the vertical portion of track 9 causes the rear section together with the back rest to assume an inclined position).

A further forward and downward movement of the front rail 19 (Fig. 12), causes the middle section to raise together with the front of the back section due to the upwardly inclined portion of tracks 10 and 11, while the rear of the back section is lowered to nearly a horizontal position carrying the back rest with it. It will be noted that at this point the lever 43 is engaged by the front roller shaft 60 whereby further forward movement is impeded by the springs 46, thus compensating the otherwise unbalanced weight of the front bed section.

A further movement downward on the front rail 19 completes the second operation and brings all the bed sections to a horizontal co-planar position with the front bed section resting upon the seat ends 32.

The back rest is then turned backwardly until the end members 23 rest upon the bed frame members 15 (Fig. 3) completing the opening operations.

It will be noted that throughout the second operation the moving parts are practically balanced to provide easy movement. While the front bed section is being raised the rear section is being lowered (from Fig. 10 to Fig. 11) and the central section maintains a uniform level. While the front section is being lowered the middle section is being raised (from Fig. 11 to Fig. 12) and the rear section practically rotates without vertical movement. From the position shown in Fig. 12 to the completed position Fig. 3 the springs 46 act to compensate the otherwise unbalanced weight of the front section.

When the bed sections are in a horizontal position as in Fig. 3 the rollers 12, 13 and 14 occupy horizontally disposed sections of the tracks whereby weight or pressure on the bed-sections does not cause movement and it will be noted that the front bed-section must be raised before

lateral movement of the bed-frame can occur, assuring a rigid condition of the bed-frame.

It is noted that when the front bed-section is in position upon the seat ends 32 the catch 56 is held in a locked position and cannot be disengaged from the leg flange 55 until the front bed-section is raised.

The mattress (shown in phantom in the various views by dotted lines 21A) is not at any time subjected to excessive bending. Since the bed section is articulated at two places and the mattress is required to assume only about a right angle at the extreme ends the divided angle is only about 45 degrees. This permits the use of a standard innerspring mattress of the usual deep construction ordinarily used on stationary beds.

Due to the arrangement of the device and the position assumed by the mattress when the device is in a closed position sufficient room is provided for a mattress of full thickness without crowding and additional space is provided on top of the mattress under the seat portion for bed clothes, quilts, blankets, pillows, etc., which may be placed on the front of the mattress while the device is opened as a bed and carried with the mattress to the closed position, thus eliminating the usual awkward procedure of stuffing the bedding material into a box under the seat.

The structure herein provided also permits the use of a mattress of standard bed width without increasing the depth of the seat front-to-back nor the height of the back rest. By way of comparison with the conventional structure in which the back rest is hinged with the seat to bring the two into juxtaposition as a bed, their combined widths do not provide a bed of comfortable dimensions. Often in practice manufacturers resort to unusual front-to-back widths of seat or an excessively high back in order to provide a wider bed but this only makes an uncomfortably wide seat or an unsightly back rest and still does not provide a full-width bed. The adopted standard bed width is 54 inches and standard mattresses are made in this width, whereas a comfortable seat width is only 22 inches and a like dimension is suitable for the back rest or a total combined width of 44 inches. In the present disclosure a normal, comfortable seat width is maintained together with the usual back rest dimensions, yet a full-width, full-thickness, standard inner-spring mattress is accommodated within the structure with sufficient spare space for accessory bedding materials.

Contrary to usual objectives in folding bed davenports wherein they are designed to complete the opening or closing operations by a single movement of some part thereof, and which necessitates the use of considerable force due to the limited movement involved, the present structure is designed to lessen the labor of opening or closing by dividing the total operation into three easy stages, neither of which require any excessive exertion to perform. For instance in opening, the seat is pulled over as one operation without appreciable movement of the other parts; then the bed sections are moved into place as another operation; and lastly the back rest is turned back into place. These easy operations are reversed to close the device into seating position.

It will be observed that in the present structure, without pulling the davenport itself away from the wall, the rear edge of the mattress is some distance from the back rest when in a

bed position providing ample room for bed covers to drape over the edge. This is more desirable than a structure wherein the mattress or bed portion abuts against the back rest or against a wall when opened.

Provision is made for a so-called soft front seat portion wherein a deep spring action is allowed. While the presently shown device embodies a stationary seat it is obvious that the separate loose cushion structure can be substituted by providing a thin padded base on the base springs.

I claim:

1. A bed davenport comprising a housing including end members; a seat portion hinged with the housing and adapted to be turned over forwardly into an inverted position in front of the housing; a sectional mattress frame, the sections of which are interconnected by hinge means; roller means carried by certain of said sections; tracks carried by said housing end members for engaging said rollers, and to support and guide the latter to carry said roller carrying sections from a closed position within said housing to a horizontal bed-position; said mattress frame having a frontal section adapted to be disposed horizontally at the bottom of said housing when in a stored position; link means interconnecting said frontal section and said hinged seat portion for carrying said frontal section from said stored position to a horizontal position co-planar with said roller carrying sections when the latter are horizontally disposed in bed-position; means forwardly of said housing for supporting said frontal section; and a back rest portion articulated with the rear of the mattress frame and adapted to be carried by said frame from a vertically disposed seating position to a horizontal position when the mattress frame is horizontally disposed, said back rest being adapted to be hinged backwardly from said last named position.

2. In a bed davenport, a housing including end portions; a bed frame comprising articulated bed sections including a front section adapted to be disposed in a horizontal position at the bottom of said housing when in a folded position; rollers carried by said bed frame sections; tracks carried by said housing end members for supporting said rollers; link means for carrying the frontal edge of said articulated bed frame; said link means and said roller and track means being adapted to carry said frame from a folded position within said housing with the front section thereof horizontally disposed near the bottom of said housing to a horizontal co-planar position partly within and partly without said housing; and supporting means for the forward portion.

3. A combination bed-davenport comprising a stationary housing including end members; a mattress support having an outer peripheral frame and interconnecting spring fabric, said frame including sectional articulated end members; rollers carried by said articulated end members; tracks carried by said housing end members, said rollers and said tracks being adapted to carry portions of said mattress support from a folded position to a horizontally disposed extended position; link means adapted to carry the front portions of said mattress support from a horizontal non-inverted position at the bottom of said housing to a horizontal position co-planar with said other portions; and supporting means for said link carried portion when in said last named position.

4. A combination bed-davenport comprising a stationary housing including end members; a sectional articulated mattress frame adapted to be folded within said housing with a rear portion extending uprightly at the rear of said housing and a front portion lying horizontally near the bottom of said housing; a separate seat member articulated with said housing for inversion forwardly of said housing; a separate back rest member articulated with said rear section of the mattress frame and adapted to be carried by said frame; said seat member when in a seating position being in spaced relation with said front section and said back rest member being in spaced relation with said rear section whereby a mattress may be interposed therebetween; means for carrying said rear section together with said back rest from a vertical position to a horizontal position; means for simultaneously transferring said front portion of said mattress support from a horizontal position at the bottom of said housing to a horizontal position co-planar with said rear section, said back rest being adapted to be turned rearwardly to an inverted upright position when said mattress frame is in a co-planar position; and a support for said front section.

5. A bed davenport comprising a stationary housing having end members; a seat portion adapted to be turned forwardly to an inverted position in front of said housing; a mattress frame having a number of articulated sections; supporting rollers carried by certain of said mattress frame sections; tracks carried by said housing end members, said rollers and said tracks cooperating to transport said rollers supported frame sections from a stored position within said housing to a co-planar horizontal bed position; supporting means comprising a single pair of links for transporting a frontal section of said mattress frame from a stored position within said housing to a horizontal position co-planar with said other sections; and supporting means carried by said invertible seat for receiving said frontal section.

6. A bed davenport comprising a stationary housing including end members; a mattress frame having a rear section, a central section articulated with said rear section and a frontal section articulated with said central section; a train of rollers carried by said rear and central sections; track means carried by said housing end members, said rollers and said tracks being adapted to transfer said rear and central sections from a stored position to a horizontal bed position, said stored position of the rear section constituting a vertical position at the rear of said housing, said stored position of the central section constituting an inclined position at the rear and bottom of said housing, said stored position of said frontal section being horizontally at the bottom of said housing; said track means comprising a separate track for each roller; and link means for supporting the forward edge of said frontal section, said link means being adapted to guide said frontal section from a position at the bottom of said housing when stored to a position co-planar with said other sections when the latter are horizontally disposed.

7. A bed davenport comprising a housing including end members; a seat portion hinged with the housing and adapted to be turned over forwardly into an inverted position in front of the housing; a sectional articulated mattress frame adapted to be folded within said housing with a

rear portion extending uprightly at the rear of said housing, a front section lying horizontally near the bottom of said housing and an intermediate section inclined at the rear and bottom of said housing; roller and track means for supporting and guiding said rear and intermediate sections from said stored position to a horizontal co-planar position at bed height, and link means interconnecting the seat portion and the front section and adapted to carry the front section from said stored position to a horizontal position forwardly of and co-planar with the other sections.

8. A bed davenport comprising a housing; a seat portion hinged with said housing and adapted to be turned over forwardly into an inverted position in front of said housing; a

5 mattress frame having inter-hinged sections adapted to be folded within said housing with the rear section vertically disposed at the rear of said housing and the front section disposed horizontally at the bottom of said housing; link means associated with the seat portion for elevating the forward edge of the front section as the seat portion is turned forward and for carrying said front section to a position forwardly of said housing and in superposed relation to said inverted seat portion, and roller and track means for supporting the remainder of said mattress frame and for guiding the latter to a horizontal position at bed height as said front section is moved to its forward position.

HOMER W. YOUNG.
